UNITED STATES PATENT OFFICE.

THOMAS CHARLES HARTLEY, OF SPOKANE, WASHINGTON.

GLAZIER'S POINT-SETTER.

1,134,334.

Specification of Letters Patent. Patented Apr. 6, 1915.

Application filed March 16, 1914. Serial No. 325,146.

To all whom it may concern:

Be it known that I, THOMAS CHARLES HARTLEY, a citizen of the United States, residing at Spokane, in the county of Spokane 5 and State of Washington, have invented new and useful Improvements in Glaziers' Point-Setters, of which the following is a specification.

This invention relates to improvements in 10 glaziers' point setters.

It is one of the objects of this invention to provide a point setter which is capable of setting points in a sash bar or the like in such spaced relation with respect to the glass 15 as to avoid breakage.

A further object is to provide a point setter capable of setting points in angular relation to the glass, and also, in spaced relation with respect thereto.

20 Further objects and features of the invention will be more fully described in connection with the accompanying drawing and will be more particularly pointed out in and by the appended claims.

25 In the drawing:—Figure 1 is a view in side elevation of one embodiment of my invention showing the setter ready to deliver points to a sash. Fig. 2 is a vertical sectional view with parts in a different position. Fig. 3 is a sectional view on line 3—3 of Fig. 2. Fig. 4 is a sectional view on line 4—4 of Fig. 3. Fig. 5 is a sectional view on line 5—5 of Fig. 4. Fig. 6 is a perspective view of my improved tool shoe or elevator. Fig. 35 7 is a perspective view of one of the points. Fig. 8 is a plan view of one end of a driver employed in the device of my invention.

Like characters of reference designate like parts throughout the different figures of 40 the drawing.

As shown, my invention includes a frame provided with a point holder 1, having a vertically elongated chamber 2 in which superimposed points 3 may be disposed with one corner in advance. The frame is also provided with a hand grip 4 which is formed integral with the holder 1, by means of a connecting portion 5. Depending from the hand grip 4, is a supporting leg 6 adjustably 45 connected with a tilting block 7, which may be dove-tailed in the leg 6 so as to be vertically slidable with respect thereto. A set screw 8 may be employed to lock the frame and tilting block from movement away from 50 an adjusted position to tilt the holder 1, or

rather its delivery end, at any desired angle from a parallel position with respect to the glass.

The delivery end of the holder is designated at 9 and I prefer to dispose a hardened wearing plate between said end and the driver, to take up wear, said plate 10 having an opening 11, shaped to conform to the type of point used. The driver is provided with a point engaging end 12 which is slidable beneath the wearing plate 10 and I preferably bend up the margins 13, of the driver to slidably engage the edges of the wearing plate 10 and the sides of the holder 1, as clearly shown in Fig. 5. The terminal 65 of the driving end is jawed, as indicated at 14, to engage the rear corners of the points when the latter descend through the wearing plate into the plane of the driver. It 70 will be clear that the jaw of the driver will 75 always be held in registry with the delivery opening of the wearing plate.

The end of the driver 12, remote from the jawed end, is connected with a driver head 14' having a rod 15 which is slidable in an 80 opening of elongated form in the leg 6, as indicated at 16. Said rod also extends through an elongated opening 17, in the tilting block 7. An expansively acting spring 18 is interposed between the head 14' and the leg 6 to normally advance the driver toward a delivering position. The top of the head 14', is provided with an adjustable release plate 19 which is shown pivoted at 85 20 to said head. A spring 21, secured to said release plate 19, engages the head and normally acts to tilt the forward end of the plate upwardly. Set screw 22, threaded into plate 19, may be set against the head 14' to 90 limit tilting movement of the release plate under the action of its spring, the latter permitting trigger movement of the release plate, as will presently appear.

A trigger lever 23, is pivotally mounted 100 on the frame of the tool, at 24, and is provided with an angle end 25 adapted to be gripped by the fingers of the user and drawn up into the position shown in Fig. 2, to retract the driver. A spring 26 is mounted on the frame, at 27 and extends beneath a stud 28 so that its free end will engage a notched portion 29 and normally act to return the lever from the position shown in Fig. 2, to the position shown in Fig. 1. The trigger lever is provided with a trigger 105 30 110

which is adapted for engagement with the end of the release plate 19, as shown in Fig. 2, to retract the driver 12. Retraction of the driver 12 will compress spring 18 so that when trigger 30 releases plate 19, spring 18 will advance the driver into a delivery position. The trigger may then be advanced over plate 19 by spring 26, depressing plate 19 so as to assume engaging relation with

10 the end thereof.

When a driver is advanced along or upon the glass in a manner to drive the point into the sash in close parallel relation with the glass, the operation of driving the point 15 almost invariably results in cracking or nicking the glass thereby causing serious loss. It is not essential that the points be driven close to the glass so as to engage the same as these points merely serve to hold the 20 glass until the putty is applied.

Now it is one of the features of this invention to elevate the tool so that the points will be driven into the sash in spaced relation with respect to the glass so as to permit 25 the putty to be squeezed between the points and the glass and thereby form a cushion and reduce the danger of straining and cracking the glass.

In the particular form shown, I provide 30 elevating or spacing means for the tool which is in the form of a shoe indicated as a whole, at 31. The shoe is U-shaped in form, the base 32 serving to elevate or space the driver 12 away from the glass by being 35 disposed beneath the driver. The legs or sides of the shoe, as indicated at 33, extend up along the sides of the holder 1 to which they may be secured by screws 34 so that the improvement may be attached to any of the 40 tools now in use. It will be seen that the shoe not only functions as a spacer, but also, as a wearing guide for the driver. Shoes having bases of different thickness, may be 45 provided to space the points the desired distance from the glass. By tilting the frame, with the tilting adjusting means previously described, the points may be driven in spaced relation and also at an angle to the parallel, with respect to the glass. A fol- 50 lower 35, provided with a weight 36, may be

used to force the points downwardly in the holder 1.

It is believed that the utility and advantages of my invention will be fully understood from the foregoing description, and while I have herein shown and described one specific form of my invention, I do not wish to be limited thereto, except for such limitations as the claims may import.

I claim:

1. In a glazier's point setter, a frame provided with a point holder and a supporting leg, tilting means for the supporting leg for tilting the frame, and a driver movable in said tilting means for driving the points 65 from the holder into the sash at an angle to the glass in accordance with the angle of tilt of the frame, substantially as described.

2. In a glazier's point setter, a frame provided with a point holder and a supporting leg, a tilting block for said leg, means for adjusting said block with respect to said leg to tilt the frame, an elevating shoe attached to the holder, and a driver structure having one portion slidable between said 75 holder and shoe and another portion slid- able in said leg and block, substantially as described.

3. In a glazier's point setter, a holder structure having adjustable tilting means, 80 and a driver having one portion slidable in said structure and another portion slidable in said means, substantially as described.

4. In a glazier's point setter, a holder for the points having a delivery end, a hardened wearing plate at said end, a shoe for elevat- 85 ing the holder with respect to the glass and being secured to the holder, and a driver slid- able between said wearing plate and shoe and having bent-up portions engaging 90 said wearing plate to guide said driver to a straight line of travel, substantially as de- scribed.

In testimony that I claim the foregoing as my own, I hereby affix my signature in the presence of two witnesses.

THOMAS CHARLES HARTLEY.
